United States Patent Office.

W. B. NOYES AND C. S. BAKER, OF MANCHESTER, NEW HAMPSHIRE.

Letters Patent No. 80,871, dated August 11, 1868.

IMPROVED SAW-SET AND GAUGE.

The Schedule referred to in these Letters Patent and making part of the same.

TO ALL WHOM IT MAY CONCERN:

Be it known that we, W. B. NOYES and C. S. BAKER, of Manchester, in the county of Hillsborough, and State of New Hampshire, have invented certain new and useful Improvements in Combined Gauge, Square, and Wrench for Saws; and we do hereby declare that the following is a full, clear, and exact description thereof, reference being had to the accompanying drawings, and to the letters of reference marked thereon, which form a part of this specification, in which—

Figure 1 represents a side view of our gauge.

Figure 2 is a plan view of the same, and

Figure 3 an end view.

The nature of our invention consists in the construction of certain new and useful devices for gauging and setting saw-teeth, when the same are arranged substantially in the manner hereinafter specified.

To enable others skilled in the art to make and use our invention, we will now describe its construction and operation.

A represents a metal bar, shaped as seen in the drawing, to which the hereinafter-described devices are attached.

B designates a semicircular elevation, with an opening in it to correspond with that in a common saw-set.

One end of the bar A is formed into a square by the rectangular piece g, with shank n attached to it.

Through shank n a screw, d, is inserted, and a corresponding screw is inserted through bar A. These screws point inwardly, and are nearly in a line.

The operation of our gauge, square, and wrench is as follows: When a saw requires setting, use the set B for that purpose. In case the teeth should be irregularly set, pass the saw-teeth successively between the screws d d, the said screws having been previously adjusted. If, by this operation, teeth on either side of the saw are found out of line, the set B will be used to bring them in position. The end, g, may be used as a wrench.

Having thus described our invention, what we claim, and desire to secure by Letters Patent, is—

The within-described device, for gauging and setting the teeth of saws, substantially as described.

In testimony that we claim the foregoing as our own, we affix our signatures in presence of two witnesses.

W. B. NOYES,
C. S. BAKER.
